UNITED STATES PATENT OFFICE.

FRANK D. FULLER, OF CHICAGO, ILLINOIS, ASSIGNOR TO THE LUDINGTON NOVELTY COMPANY, OF LUDINGTON, MICHIGAN.

DESIGN FOR A GAME-BOARD.

SPECIFICATION forming part of Design No. 33,604, dated November 20, 1900.

Application filed October 10, 1900. Serial No. 82,655. Term of patent 14 years.

To all whom it may concern:

Be it known that I, FRANK D. FULLER, a citizen of the United States, residing at the city of Chicago, in the county of Cook and 5 State of Illinois, have invented and produced a certain new and useful Design for a Game-Board, of which the following is a specification.

This invention relates to a design for a 10 game-board.

The design is fully illustrated in the accompanying drawing, in which the figure shown is a detail perspective view of a game-board constructed according to my design.

15 As shown in the drawing, the leading or material features of my design consist of a series of concentric circles B, with the circle

B' differentiated from the other circles, and a central spot or point D. These circles are intersected by the lines C, which radiate from 20 the center. Circles outside of the circle B' are also intersected by the lines C'.

Having thus described my invention, what I claim as new, and desire to secure by Letters Patent, is—

The design for a game-board, as herein shown and described.

In witness whereof I have hereunto set my hand and seal in the presence of two witnesses.

FRANK D. FULLER. [L. S.]
